UNITED STATES PATENT OFFICE.

ROBERT S. ELLIOTT, OF KANSAS CITY, MISSOURI.

TARGET-THROWING TRAP.

Application filed August 24, 1921. Serial No. 494,813.

To all whom it may concern:

Be it known that I, ROBERT S. ELLIOTT, a citizen of the United States, residing at Kansas City, in the county of Jackson and 5 State of Missouri, have invented a certain new and useful Improvement in Target-Throwing Traps, of which the following is a complete specification.

This invention relates to target throwing traps. The most efficient target trap in use is open to objection in that the "table" must be oscillated to direct the targets at different angles, by the boy who feeds the targets to the trap. The oscillation of the 10 table is fatiguing, and the boy soon finds that by timing the feeding of the targets with the oscillation of the trap, the work is easier. The two operations in such case, are however, so rhythmic, that some "shooters" 15 are able to foretell or "dope" the direction in which successive targets will be thrown, and are thus enabled to make better scores than others of equal or greater ability who depend wholly on their quickness of eye and 20 hand.

Another objection to such traps is that there is about an eight or ten per cent breakage of targets by the impact of the throwing arm on the target, due to the fact 25 that the boy, in feeding the trap, does not always exercise such care as to insure the retention of the target in contact with the throwing arm until the operation of the latter begins. This trouble is, of course, 30 greater than would be the case if the boy was relieved of the duty of oscillating the trap.

My object, therefore, is to produce a target trap which will throw "singles" and 40 "doubles" efficiently but which is not open to the objections above enumerated. In other words, my object is to produce a trap which is efficient in throwing the target; in which breakage by the trap will be almost 45 obviated; and which will make "doping" of the target practically impossible. More specifically, my object is to produce a trap by which target can be thrown at any angle between extreme "lefts" and "rights" from 50 a stationary table, and by which "doubles" can be thrown with the same facility as "singles," and in which the targets are yieldingly held where set by the attendant re-

gardless of the pitch or inclination of the table.

With the objects mentioned in view the invention consists in certain novel and useful features of construction and combinations of parts as hereinafter described and claimed; and in order that it may be fully 55 understood, reference is to be had to the accompanying drawing, in which:

Figure 1 is a side elevation of a conventional trap, with the pedal attachment omitted, a new table and the target holding 60 equipment in place.

Figure 2 is a top plan view of the same.

Figure 3 is a cross section on the line III—III of Figure 2.

In carrying out the invention I have 70 found that one of the common and well known traps can be employed with excellent result by leaving off the pedal feature and by providing the trap with either a new table or an extension for the old table and 75 by equipping the trap with a retainer whereby the target or targets shall be yieldingly held in operative engagement with the throwing arm, when placed in position by the boy.

Referring now to the drawing in detail, 1 indicates the base of the trap, anchored as shown or otherwise to a suitable foundation, and 2 is an angle frame pivoted at 3 on the base 1, and in order to secure the angle 85 frame at the desired angle or inclination for insuring the direction of the target at the desired trajectory, the angle frame is provided at its rear end with a bolt 4 extending through a segmental slot 5 in the 90 base, and a clamping nut 6 engages the bolt to secure the frame rigidly at the desired point of adjustment.

Rigidly secured to the upper part of the angle frame in any suitable manner, is a 95 table 7, the same being made stationary instead of rotatable as in the usual trap. Because of this fact the table is made somewhat larger than the usual table to constitute a guide for the targets thrown to the 100 right, after they leave or become disengaged from the throwing arm, and to guard against any chance of the tilting and hence imperfect flight of the target as it leaves the table, the front edge of the latter extends 105 substantially at right angles to the line of

flight of the target when traveling in a direction centrally between the two extreme lines of flight to the left and to the right.

Mounted upon the table so as to oscillate across the face thereof is the throwing arm 9, the same being pivoted to the front end of the angle frame 2, and at the lower end of the pivot there is a crank 10 connected by a retractile spring 11 to a swing arm 12 depending from said frame. The lower end of the swing arm 12 and the rear end of said spring are linked to the trap springing rod 13 which is operated in the customary manner for the purpose of imparting the throwing movement to the throwing arm, and the latter is returned to its initial position by the torsional spring 14, when the pull on the rod 13 is relaxed.

The throwing arm is provided with a rubber strip 15 for engagement with the target 16 as shown most clearly by Figures 2 and 3, the target resting flatly upon the table, and secured to the latter are segmental stops 16^a and 17, which serve, in the case of a single target, as indicators to define the limits of the movement of the target with reference to the fulcrum or pivot for the arm 9. When a target is placed against the stop 16^a, it will be so positioned as to be thrown to the extreme left and, when placed against the stop 17, it will be so positioned as to be thrown to the extreme right. When a target is placed centrally between the stops 16^a and 17, it will be thrown directly forward. As it is moved from such central position toward the stop 16^a (and toward the pivot or fulcrum of the arm 9) it will be thrown to the left, the amount of its deflection toward the left increasing as it approaches such stop and pivot or fulcrum. As it is moved from such central position toward the stop 17 (and away from the pivot or fulcrum of the arm 9) it will be thrown to the right, and the amount of its deflection toward the right will increase as it approaches such stop and recedes from such fulcrum or pivot. In other words, the arm 9, when in its latched position preparatory to throwing, provides an extended seat between the stops or indicators 16^a and 17 against which a target on the table may be placed at varying distances from the fulcrum or pivot of such arm; and the target, according to its position on such arm and its distance from such fulcrum or pivot, will be thrown to the extreme right, to the extreme left, or in any direction intermediate such extremes. Furthermore, by using stops for the indicators, a pair of targets may be placed therebetween and seated against the arm, with their proximate portions in contact—as indicated in Fig. 2. When a stationary table is used to accomplish these results, it is advisable to provide means to yieldingly hold the target against the

throwing arm during the early part of the movement of the latter, and it is also advisable to guard against accidental shifting of the target on the table, this trouble occurring frequently when the angle frame is adjusted to set the table to throw the target at a sufficiently high angle to counteract the effect of a wind traveling in the same direction as the target, as otherwise the wind tends to flatten out the target and shorten its travel. To accomplish the two purposes mentioned, a clamp or retainer is secured to the table and adapted for pressing lightly upon the upper face of the target or targets. The preferred means for accomplishing this purpose comprises a skeleton or U-shaped frame 18, mounted upon a block 19 bolted as at 20 to the table, the frame overlying the block and throwing arm and having a depending flange 21 fitting against the outer edge of the block and mounted loosely upon a pair of bolts 22 projecting from the block. The bolts carry nuts 23 and lock nuts 24, and springs 25 are mounted on the bolts and interposed between the nuts 23 and the flange 21 of the retainer to hold the same yieldingly in the position indicated most clearly by Figure 3, so that the frame or retainer shall clamp the targets lightly upon the table and retain them in engagement with the rubber strip of the throwing arm for a sufficient length of time to insure proper rotation of the target as the latter, under the throwing movement of said arm, rolls outward upon the strip while being bodily swung around by the arm.

It will be apparent that the retainer will hold the target against accidental movement wherever placed, that is whether in contact with one of the stops 16^a—17, or at any point between the same, and that the connection of the retainer with the block permits the clamping edge of the former sufficient vertical play to accommodate targets of slightly different thickness.

A common type of trigger mechanism is employed to hold the throwing arm in "cocked" position as shown, and to release it for operation, said mechanism comprising a latch-bolt 26 held yieldingly-elevated by a spring (not shown) and a trigger 27 pivoted to frame 2 and adapted to have its depending arm 28 struck by the yoke 12 when the rod 13 is pulled rearwardly to operate the trap, the trigger being connected in a well-known manner to withdraw the latch-bolt from the path of the throwing arm to permit the latter to operate. Upon the return of the arm as hereinafter explained, it depresses the latch-bolt and as it passes this latter is yieldingly reelevated to its original position to hold the arm in "cocked" position.

In operation, a boy sitting under the customary low shed beneath which the trap

is stationed, places a single target or a pair of targets on the trap, shoving the target or targets under the retainer. In so doing, due to the proportion and arrangement of the parts, each target is disposed against the rubber strip of the throwing arm and hence will be guarded against such impact as might fracture the target or targets. It will also be noted that as the retainer holds the target securely, the boy is not required to exercise any particular care in placing single targets at a particular point with respect to the stops 16a—17. For this reason, the direction in which targets are likely to be thrown, cannot be determined by the shooter, and the trap affords the fairest test of marksmanship.

As the rod 13 is pulled back as customary, the spring 11 is tensioned and yoke 12 swung rearwardly, said yoke by striking the trigger 27 and withdrawing the latch-bolt 26 from the path of the throwing arm so that the tensioned spring 11 may operate the arm to "throw" the target or targets, this movement of the arm tensioning spring 14 so that it shall return the arm to operative position. As this is accomplished, the latch-bolt automatically engages and holds the arm until the next pull is applied on rod 13. As the trigger mechanism is of common and well-known construction and operation, its construction is not illustrated fully or in detail, and no claim is made to it.

From the above description it will be apparent that I have produced a trap throwing target which embodies the features of advantage set forth as desirable in the statement of the objects of the invention, and while I have illustrated and described the preferred embodiment of the same, it will be apparent that it is susceptible of modification in various particulars without departing from the principle of construction and mode of operation involved.

45 I claim:

1. A target throwing trap comprising a table, a throwing arm arranged to sweep across the face of the table, means for latching the said arm in the same initial position preliminary to its throwing operations, and means carried by the table and projecting forwardly above said arm, when the latter is in said initial position, for retaining one or more targets against said arm.

55 2. A target throwing trap comprising a table, a throwing arm arranged to sweep across the face of said table, means for latching the said arm in the same initial position preliminary to the throwing operation, and yieldable means carried by the table and projecting forwardly above said arm, when the latter is in said initial position, for lightly clamping one or more targets against said arm.

65 3. A target throwing trap, comprising a

pivoted frame pitched at a slight angle upwardly and forwardly from its point of support, a stationary table carried by and projecting forwardly and laterally from the said frame, a throwing arm pivoted to said frame and constituting, while in its initial position and prior to its throwing movement, a seat on which a target on said table may be placed at varying distances from the fulcrum or pivot of such arm, and means to latch the said arm in the said initial position preliminarily to the throwing operations thereof. 70 75

4. In a target throwing trap, an upwardly and forwardly inclined stationary table 80 upon the rear part of which a target is adapted to rest flatly, a retainer carried by the table and overlying and spaced therefrom and capable of slight vertical movement, yielding means tending to clamp the retainer lightly upon the target, and an arm for sweeping across the table to disengage the target from the retainer and project the former into space. 85

5. A target throwing trap comprising a 90 pivoted frame pitched at a slight angle upwardly and forwardly from its point of support, a stationary table carried by and projecting forwardly and laterally from said frame, and a throwing arm pivoted to said frame and constituting, while in the same initial position and prior to its throwing movement, a seat on which a target on said table may be placed at varying distances from the fulcrum or pivot of such 95 arm. 100

6. A target throwing trap comprising a pivoted frame pitched at a slight angle upwardly and forwardly from its point of support, a stationary table carried by and projecting forwardly and laterally from said frame, target stops on said table adapted to receive a pair of targets simultaneously therebetween, and a throwing arm pivoted to said frame and constituting, when in 110 latched throwing position, a seat for both such targets so interposed between such stops as well as a seat on which a single target may be placed against or between said stops and at varying distances from 115 the fulcrum or pivot of such arm. 105

7. A target throwing trap, comprising a pivoted frame pitched at a slight angle upwardly and forwardly from its point of support, a stationary table carried by and projecting forwardly and laterally from the said frame, a throwing arm for sweeping across the table for throwing targets therefrom at different points along the front edge thereof, and means carried by the table 120 for holding one or more targets on the table and against the throwing arm during the initial portion of the throwing movement of the latter and at varying distances from 125 the fulcrum or pivot of such arm. 130

8. A target throwing trap comprising a frame, a table rigid therewith, a yieldingly-depressed retainer carried by and overlapping the table to hold thereon one or more targets, a throwing arm, and means for latching said arm in an initial position underlying the retainer and back of the free or overlapping edge thereof, whereby

the said arm, when released, will move forwardly from under the retainer and across the table to sweep the target or targets from engagement with the retainer and forwardly upon and off the table. 10

In witness whereof I hereunto affix my signature.

ROBERT S. ELLIOTT.
